UNITED STATES PATENT OFFICE.

RICHARD ABRAM, OF RIVERSIDE, ILLINOIS.

AIR-REGULATING DEVICE FOR INTERNAL-COMBUSTION ENGINES.

1,400,506.

Specification of Letters Patent. Patented Dec. 20, 1921.

Application filed July 3, 1919. Serial No. 308,643.

To all whom it may concern:

Be it known that I, RICHARD ABRAM, a citizen of the United States, residing at Riverside, in the county of Cook and State 5 of Illinois, have invented certain new and useful Improvements in Air-Regulating Devices for Internal-Combustion Engines, of which the following is a specification.

One of the objects of the invention is to 10 provide an improved air intake conduit, or device for internal combustion engines.

Another object is to provide an improved 15 automatic valve for regulating the air supply, substantially proportional to the speed of the engine.

A more specific object is to provide a 20 valve, responsive to the velocity of air passing through the intake conduit, which is automatically opened and closed to vary the mass of air passing into the engine, as its 25 velocity tends to be varied, by the changing speed of the engine, thereby maintaining substantially uniform, or constant the velocity of the air, under conditions wherein a variable quantity, or mass of air is supplied to 30 the engine, in a given time.

And still another object of the invention 35 is to provide a convenient means whereby to vary the thermal temperature of the air supplied to the engine by the disclosed controlling device, easily accessible, without disturbing the automatically operable valve adapted to maintain the constant velocity.

Other, further and more specific objects 40 of my invention will become readily apparent to persons skilled in the art from a consideration of the following description when taken in conjunction with the drawings, wherein:

Figure 1 is a side elevation of an engine, 45 showing my air inlet attachment applied thereto.

Fig. 2 is an enlarged section, taken on line 2-2 of Fig. 1.

Fig. 3 is a side elevation showing parts in section.

Fig. 4 is a plan view of the device looking 50 into the upper end of the air heating stove.

Fig. 5 is a transverse section, taken on line 55 5-5 of Fig. 3.

In all the views the same reference characters are employed to indicate similar parts.

10 represents an internal combustion engine mounted on an automobile 11, of well known type. 12 is the carburetor connected to the intake manifold 13. 14 is the exhaust

manifold. The manifolds are held in position by the well known crab or clamp bracket 15, bearing on ears 16, projecting laterally from the respective manifolds. 17 is a foot 60 board of the automobile and 18 is the dash board, or instrument board.

The device 20 consists of an air conduit made, preferably, in L-shape, having its lower horizontal end 21 connected to the intake orifice of the carburetor 12, and its upper vertical end terminating in a stove 22, which partially surrounds the exhaust manifold 14, as more clearly shown in Fig. 2, so that air that is drawn into the conduit 20 65 must pass around a portion of the hot exhaust pipe, in substantial intimate contact therewith, and then pass between the manifold and the outer walls of the stove, as at 24. The stove consists of a part that passes 70 about and under the lower part of the manifold and spaced away therefrom, as at 24, and another vertical lip part 25, spaced away from the manifold, as shown at 24, so that the air passing into the conduit, through 75 the stove and between it and the manifold into the intake of the carburetor, must pass near the hot manifold and become heated thereby before it enters the carburetor. One of the crabs or clamps 15 are employed for 80 holding the flat lip 25 of the stove, in position in association with the manifold, just as these clamps are used for holding the manifold on the body part of the engine and, therefore, no change of structure is necessary 85 in applying my device to an engine of well known type.

Located below the stove 22, in the conduit 26, is a valve 27, pivoted, as at 28, controlled by an arm 29 and adapted to close a port 30 90 in the conduit 26. When the valve 27 is open, as shown in dotted lines in Fig. 2, air will enter the port 30 and not be drawn through the openings 24 around the manifold and therefore colder air will be supplied to 95 the engine. When the valve 27 is entirely closed, as shown in full lines in Fig. 2, then all of the air supplied to the engine will pass around the exhaust manifold, through the openings 24 supplied by the stove, and directly into the engine, through the conduit 100 105 26, the cold air being prevented from entering the conduit by the port 30 being entirely closed by the valve 27. The arm 29, which controls the valve 27 is connected by a link 31 to a crank arm 32' and to the handle 32 on the inside of the automobile and support- 110

ed by the instrument board 18, so that the relative quantity of hot air and cold air desired to be supplied to the engine may be varied by the position of the valve 27, in the conduit 26. If the valve is part way open, then the hot air and the cold air supplied to the engine will be proportional to the areas through which the respective streams of air will enter the conduit 26.

10 This feature of my invention controls the temperature of the air that enters the engine. The device is, therefore, highly desirable, when starting the engine cold mornings, before the engine becomes sufficiently heated to entirely volatilize the fuel contained in the charges supplied to the respective cylinders.

After the engine has been started, then the proportions of hot and cold air may be readily regulated by movement of the handle 32 which moves crank arm 32' and which is connected to the rod carrying the handle 32 and to which rod 31 is also connected.

15 The conduit 26 is curved, as at 33, and the horizontal extension 26' from the curve, contains an automatically operable check-valve 34. The valve 34 is pivoted, as at 35, and is normally closed, by effect of gravity, as clearly shown in Fig. 3. A perforation 20 36 passes diagonally through the valve 34, and when the valve is in closed position, the aperture 36 is at an angle of about 15 degrees from the axis of the conduit part 26' and as the valve 34 is being opened, the axis 25 30 of the perforation 36, gradually approaches parallelism with the axis of the conduit 26'.

Now when the engine is operating slowly, and the quantity of the air coming through the conduit 26 and 26' is relatively small, a sufficient amount may pass through the orifice or perforation 36, but if there is a tendency of the air to increase its velocity, it will impinge more forcibly upon the wall 37, of the opening 36, which is inclined from the natural path of the air, and open the valve 34 substantially proportional to the speed of the engine, until the opening of the port, normally closed by the valve 34, will increase the volume or mass of air passing through the valve port, opened by the valve, thereby maintaining the velocity substantially constant, and therefore with constant velocity, more complete and uniform pulverization of the fuel charge will be accomplished. The tendency of the air, coming through the chambers 38 and 39, is to move in straight lines and, therefore, the resistance offered by the oblique wall 37 of

the perforation 36 has the effect to open the valve 34 and direct a portion of air 60 through the port thus opened, while a continuing stream will flow through the perforation 36. The perforation 36 also provides a means for supplying some air at all times independently of the movement of the valve. 65

While I have herein shown a single embodiment of my invention, for the purpose of clear disclosure, it will be manifest to persons skilled in the art, that considerable variation may be made within the scope of 70 the appended claims.

Having described my invention, what I claim is:—

1. An air intake for internal combustion engines having in combinative association, 75 a conduit, for connection at its discharge end to the inspiration port of a carburetor; a stove, at its other end, for location adjacent the exhaust manifold of the engine to heat the incoming air, said conduit having a port 80 between the stove and its discharge end; an inwardly opening valve for said port to control the proportion of hot and cold air entering the conduit by restricting the conduit, and a gravity operable, perforated valve 85 in the conduit, to automatically maintain constant the velocity of the air supplied to the engine, through the operation of the first mentioned valve, under different conditions of speed of the engine. 90

2. An air intake, for internal combustion engines having in combinative association, a conduit, for connection at its discharge end to the inspiration port of a carburetor; a valve in said conduit, normally closed, 95 adapted to be automatically opened by incoming air and having an air inlet opening, the axis of which is at an angle to the normal path of the incoming air, whereby to open the valve by increased velocity of the 100 air.

3. An air intake for internal combustion engines having in combinative association, a conduit, for connection at its discharge end to the inspiration port of an engine; a 105 gravity operable valve in said conduit adapted to be opened by the incoming air; and a port through said valve, the axis of which is at an angle to the normal path of the air and which approaches parallelism with 110 said path as it is moved toward open position.

In testimony whereof I hereunto subscribe my name.

RICHARD ABRAM.
